UNITED STATES PATENT OFFICE

JOSEPH J. McDONALD, OF LANSFORD, PENNSYLVANIA

DISPENSING CAP

Application filed December 6, 1930. Serial No. 500,616.

The present invention relates to a dispensing cap designed particularly for use on collapsible tube containers such as are commonly used in the merchandizing of toothpaste, shaving cream and the like.

The prime object of the invention resides in the provision of a cap which may be threaded on the neck of the tube and manipulated to open or closed position without detaching the cap or any part thereof from the tube.

Another very important object of the invention resides in the provision of a cap of this nature which is exceedingly simple in its construction, inexpensive to manufacture, strong and durable, thoroughly efficient and reliable in use and operation, easy to manipulate, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is an elevation of a collapsible tube with my improved cap mounted thereon, the lower portion of the cap being shown in section.

Figure 2 is a sectional view taken substantially on the line 2—2 of Figure 1, and

Figure 3 is a transverse section through the cap.

Referring to the drawing in detail it will be seen that numeral 5 denotes a collapsible tube container of any preferred construction having the usual dispensing neck 6 externally threaded. Numeral 7 denotes a cylinder internally threaded at one end to engage over the neck 6 and having at its other end an annular groove or pocket 8 extending inwardly from the edge of the cylinder remote from the tube neck 6. Numeral 9 denotes a sleeve 85 slidable and rotatable in the pocket 8 and

formed with an inverted L-shaped slot 10 having a longitudinal longer section *a* and a transverse shorter section *b*. A pin 11 is positioned in the upper portion of the wall of the cylinder 7 across the pocket 8 through the slot 10.

The upper end of the sleeve 9 is closed by a disk 12 formed thereon and having its edge corrugated so that the sleeve 9 may be easily manipulated. Obviously by pushing the sleeve 9 down into the pocket and rotating the sleeve so that the pin is disposed in the section *b*, the cap is in a locked closed position. Then by rotating the sleeve in the opposite direction said sleeve may be pulled outwardly to the position shown in Figure 1 and the contents of the tube may be squeezed therefrom through the cylinder 7 into the sleeve 9 and out through the slot 10.

It is thought that the construction, operation, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

Having thus described my invention, what I claim as new is:

Dispensing means for a tube containing paste or the like comprising a cylinder connected to the neck of the tube and having an annular slot therein extending from the free end of the cylinder to a point an appreciable distance from the other end of the cylinder, said slot forming an annular pocket, a sleeve having its outer end closed and its other end open, said sleeve being slidably and rotatably arranged in the pocket, said sleeve having an L-shaped slot therein, the long arm of which is longitudinally arranged therein and a pin 85

passing through one wall of the cylinder and through the slot in the sleeve whereby the sleeve can be moved outwardly so that a part of the slot will act as a discharge opening for the contents of the tube and by pushing the sleeve inwardly and giving it a turning movement the pin will enter the short arm of the slot to lock the sleeve in closing position in the cylinder.

10 In testimony whereof I affix my signature.
JOSEPH J. McDONALD.
